UNITED STATES PATENT OFFICE.

PAGET HIGGS, OF NEW YORK, N. Y.

THERMO-ELECTRIC BATTERY.

SPECIFICATION forming part of Letters Patent No. 241,859, dated May 24, 1881.

Application filed February 10, 1881. (No model.)

To all whom it may concern:

Be it known that I, PAGET HIGGS, a subject of Great Britain, residing at New York city, in the county and State of New York, have invented a new and useful Improvement in Thermo-Electric Batteries, of which the following is a specification, reference being had to the accompanying drawings, forming a part thereof, in which—

10. Figure 1 represents the manner of joining together the thermal couples; Fig. 2, a plan view of one battery, in sufficient detail to illustrate the principle involved; Fig. 3, a vertical section of the same, and Fig. 4 a modification of the arrangement of the thermal couples.

The object of my invention is to adapt the thermo-electric pile to permanent and constant use, whereby it may be availed of as a battery or generator of a constant and permanent electric current instead of being used, as heretofore, for laboratory and thermoscopic purposes.

To that end my improvements relate principally to the materials of which the couples are composed, and to the arrangements of the couples in the battery, and for maintaining the difference in temperature at the different ends of the couples.

Though experiments have heretofore been made for determining the electro-motive force 30 of most of the metals, yet for practical purposes such piles have heretofore been generally constructed of the easily-fusible metals—such as antimony and bismuth, (Nobili,) galena, zinc, &c.—or of alloys of similar character.

These metals and alloys are subject to various 35 objections when so used, arising mainly from their fusible character, and from their being subject to molecular disintegration under the electric action when this action is of amount

40 requisite for the practical purposes hereinbefore mentioned. To meet these difficulties I adopt as the basis of my elements the metals iron and nickel alone, or their compounds and alloys, which are practically non-fusible and 45 will endure the action of the electric current without change, and which among such elements will probably give the greatest electro-motive force. As known, the pure iron is too expensive, and nickel has great resistance to

50 the electric current. I find it best to use as

the basis of one of the elements the commercial iron, which is in all its states more or less combined with carbon and with other impurities, and to coat this, when reduced to suitable shape, with a plating of pure iron, which 55 may be laid on by electrolytic action, or otherwise. In the same way the other element of the couple is made preferably of German silver or brass, of the desired shape, and is then plated with nickel, preferably by electrolysis. 60 A plating constituting about one-third of the mass of the plate will be found to give good results, but the proportions may be varied under various conditions.

I am aware that in thermo-electric couples 65 it has before been proposed to give mechanical strength to one of the elements by constructing it of a core of steel totally insulated by an enamel coating from an exterior shell, in which case the exterior shell alone formed the effective part of the element by reason of the insulation of the core.

In constructing the battery the couples may be joined in any of the ordinary ways; but I prefer that which is illustrated in Fig. 1 of the 75 drawings, and which will be readily understood by reference to the figure. The couples may be made in the form of rings, in which case Fig. 1 would show a section of one side of the rings. When so constructed, and several 80 couples are superimposed so as to form a pile, the heat may be applied by means of a flue or other source of heat in the interior of the rings, and the outer ends may be kept cool by means of a jacket or surrounding vessel, through 85 which a circulation of water may be maintained. Such an arrangement constitutes my improved form of battery, and may be used with couples of any materials, though with the old couples it will be subject to the difficulties I have before mentioned. Such a battery is shown in a plan view in Fig. 2, and in section in Fig. 3. In these figures *a* represents the heating-flue; *b*, the metallic couples in rings, and *c* the water-jacket. The heating-flue is electrically separated from the pile by a division of mica or other electric non-conductor, and a similar provision is made to prevent contact of the different elements of the couples except at the proper points, a provision which will be readily 95 100

made by any person familiar with the general subject.

From the drawings it is seen that the elements are constructed in such a form that one is a plain flat bar or ring and the other angular, and they may be joined by making grooves in the alternately opposite ends of the flat element, into which the angular ends of the other are fitted. The grooves may be either plain or dovetailed, or part in one way and part the other, as shown in Fig. 1. This method of making the connections obviates the necessity of brazing the elements together.

Fig. 4 shows a variation in which the elements, instead of being arranged in rings around a heating-flue, are constructed of bars arranged in piles radiating from such a central source of heat. In such an arrangement the separate piles should, of course, be electrically connected with each other at their ends, in order to constitute a single battery. By arrangement of this electric connection provision might be made for using only one or any number of such piles at one time, so as to obtain currents of different strength in analogy to the arrangements by which one or more cells of a galvanic battery may be used. An obvious inversion of the above arrangement would be to apply the heat from the exterior of the ring and place the cooling device in the interior.

I am aware that the pile of a thermo-electric battery has been before arranged in a ring

around a central heating device, and this, therefore, I do not claim; but

What I do claim, and desire to secure by Letters Patent, is—

1. The combination, in a thermo-electric battery, of an element having its surface of chemically pure iron, with one having its surface of nickel, substantially as described, so that the electro-motive force is derived from chemically pure iron and nickel in contact.

2. A thermo-electric element composed of a non-fusible base directly and continuously coated or plated with another metal or alloy.

3. A thermo electric couple composed of a carbonated iron base coated with pure iron, and an alloyed or compound base infusible at low temperature, coated with nickel.

4. In a thermo-electric battery, the couples in rings about a central heating-source, in combination with the water-jacket C, substantially as described.

5. In a thermo-electric couple, the combination of the central heating-flue, the radiating piles, and the water-jacket C, substantially as described.

6. A thermo-electric couple in which the elements are connected together by a mortised joint, plain or dovetailed, substantially as shown and described.

PAGET HIGGS.
